PRESSER FOOT MECHANISM FOR SHOE
SEWING MACHINES

Otto R. Haas, North Beverly, Mass., assignor to
United Shoe Machinery Corporation, Flemington,
N. J., a corporation of New Jersey

Application November 14, 1941, Serial No. 419,072

15 Claims. (Cl. 112—60)

The present invention relates to shoe sewing machines and more particularly to improvements in presser foot actuating mechanisms for wax thread machines of the type designed for connecting the welted upper and outsole of a Goodyear welt shoe with a lockstitch seam. Machines of this type are disclosed in U. S. Letters Patent of Ashworth No. 1,169,909, of February 1, 1916, and in an application for patent of the present inventor, Serial No. 294,926, filed September 14, 1939.

In sewing together the welted upper and outsole of a Goodyear welt shoe, the resistance of the materials in the work operated upon to penetration and operation of the stitch forming devices necessitates a relatively heavy clamping pressure to secure them in place. This pressure is relieved during each sewing cycle to enable the materials to be fed a stitch length and again applied first yieldingly with a light pressure and then with a renewed heavy pressure during the succeeding stitch forming cycle. Machines of the type above referred to are heavily constructed and when operated at high speeds, according to present day sewing practices, are frequently subject to extreme wear from vibration and similar causes.

In the machines of the patent and application referred to, a mechanical presser foot actuating mechanism having either a frictional or pawl and ratchet lock is employed to hold the clamping pressure on the work during stitch formation. This lock is extremely efficient when properly adjusted but under certain circumstances, after excessive wear and accumulation of foreign matter along its frictional surfaces, becomes noisy and ineffective for the purposes intended when operated at high speeds, thus rendering the entire mechanism incapable of securing the work properly in relation to the stitch forming and work feeding devices. As a result, the spacing between stitches inserted by the machine becomes variable and difficulty is encountered by the operator in guiding the work to form an acceptable seam.

An important object of the present invention is to provide a presser foot actuating mechanism for a shoe sewing machine of the type referred to which is not subject to the limitations affecting the usual mechanisms having a mechanical presser foot lock and which may be operated entirely by hydraulically driven connections. Other objects are to provide a presser foot mechanism in which a light yielding application of clamping pressure in the mechanism

is not subject to mechanical limitations encountered in the use of springs and heavy linkages but in which the clamping pressure may be applied positively with either a light or relatively heavy force, according to the manner of adjustment for the type of work operated upon. Further objects are to simplify and improve the operation of a shoe sewing machine in which the work is secured in operating position by pressure applied between a work support and a presser foot and relieved during each sewing cycle to enable the work to be fed.

With these and other objects in view, the present invention relates to the provision in a shoe sewing machine having a presser foot and a work support for clamping and releasing the work, of a presser foot actuating mechanism comprising a liquid pressure responsive member connected to the foot and hydraulic pressure means for applying the pressure to and relieving the pressure from the responsive member during each sewing cycle. By the use of a hydraulic actuating mechanism, vibrations set up in the mechanical connections between the presser foot and the pressure responsive member are absorbed in large degree by liquid acting on the pressure responsive member, thus causing movements imparted to the presser foot actuating mechanism to be transferred accurately to the presser foot without variation from one sewing cycle to another, particularly at high speeds. Also, the connections between the presser foot and the pressure responsive member are subject to less strain and wear than the connections of the usual mechanical presser foot mechanism.

Preferably, according to this feature of the invention, the hydraulic pressure means includes a continuously driven pump and a valve actuated during each sewing cycle to control the passage of liquid from the pump to the pressure responsive member. In order to provide liquid momentarily in greater volume than furnished by the pump so that even during high speed operation of the present machine, an adequate pressure will be maintained, a pressure storage chamber is connected between the pump and the control valve. As hereinafter described, a metering device also is connected between the source of pressure and the pressure responsive member to limit the movement of the presser foot to an extent sufficient for releasing and clamping the work securely. In one form of this metering device, a cylinder provided with a piston slidably mounted therein is suitably connected in the hydraulic system to block the flow of liquid after

a predetermined movement of the presser foot by the pressure responsive member. In certain of the broader aspects of this feature, the invention may be employed to advantage with any fluid capable of being compressed and controlled accurately with a metering device, regardless of whether the fluid is expansible or incompressible.

As in most modern sewing machines, the machine in which the features of the present invention are embodied is provided with driving and stopping mechanisms for bringing the sewing shaft to rest with the stitch forming devices in predetermined relative positions. In the present form of a further feature of the invention, a by-pass valve actuated by the driving and stopping mechanisms is provided with suitable ports and properly connected to the hydraulic system to cause the work clamping pressure on the responsive member to be relieved and the work released whenever the sewing shaft is brought to rest.

Other features of the invention consist in the devices, combinations and arrangements of parts hereinafter described and claimed which, together with the advantages to be obtained thereby, will be readily understood by those skilled in the art from the following description taken in connection with the accompanying drawings, in which Fig. 1 is a view in side elevation of so much of an outsole shoe sewing machine as is necessary to illustrate a construction embodying the present features of the invention; Fig. 2 is a vertical sectional view, on an enlarged scale, of a stopping by-pass valve illustrated in Fig. 1; Fig. 3 is a vertical sectional view on an enlarged scale of a construction including a main control valve, the by-pass valve, and a metering device, all shown in Fig. 1; Fig. 4 is a horizontal sectional view of the metering device illustrated in Fig. 3; Fig. 5 is a horizontal sectional view of the by-pass valve; Fig. 6 is a view in front elevation of the by-pass valve base illustrating the passages leading to the various openings therein; and Fig. 7 is a diagrammatic view of the passages and connections in the hydraulic portions of the presser foot actuating mechanism, including flat developments of the outer surfaces on the main control valve and the stopping by-pass valve.

The illustrated machine is of the same construction and mode of operation, except as hereinafter described, as those machines disclosed in the patent and application above referred to and is provided with a curved hook needle 2 and a curved awl 4 acting together with other stitch forming devices to insert a lockstitch seam in thick heavy materials such as the welt and outsole of a leather shoe. In operation, the work is first penetrated by the awl, after which the awl retracts, followed by the needle until the hooked end of the needle is in position to receive a loop of thread. The threaded needle then retracts and the loop of thread is carried about a supply of locking thread by a shuttle indicated at 6. After the awl penetrates the work, it moves in the direction of feed a stitch length to bring the perforation formed by the awl into line with the needle. During the passage of the needle through the work, the work is held clamped between a work support 8 secured to the frame of the machine and a presser foot 10 fulcrumed on a fixed shaft 12. The stitch forming devices are actuated by either one of a pair of sewing shafts 14 and 16 provided with suitable cams and cranks to impart the proper movements to the stitch

forming devices. The sewing shafts are geared to rotate together in opposite directions and are driven through driving and stopping mechanisms constructed and arranged as in U. S. Letters Patent to Ashworth No. 1,233,539, of July 17, 1917.

In the machines of the patents and application, a cam on a shaft corresponding to the sewing shaft 14 acts on a cam lever comprising a mechanical actuating mechanism connected to the presser foot to impart the proper work clamping and releasing movements thereto to cause the work to be clamped with a uniform pressure. In the machines of the patents, an additional action of the cam enables the work to be released by movement of the presser foot away from the surface of the work through a uniform distance during each sewing cycle. The presser foot actuating mechanism in both the patents and application is connected with a spring acting after the work is released to bring the presser foot yieldingly against the surface of the work. After the presser foot is brought again the surface of the work, the cam on the sewing shaft causes the work to be compressed and the position of the presser foot to remain stationary until the next feeding movement of the work occurs.

To hold the presser foot stationary in the machine of the patents, the mechanism is locked by a friction controlled locking device in the form of a threaded rod and nut, the positions of which are maintained by preventing rotation of the nut on the threaded rod during the proper portions of each sewing cycle. The nut of the locking device in Patent No. 1,169,909 is gripped frictionally to hold it from rotation by a spring-pressed lever which is actuated to release the nut through connections to a cam lever, the motion of which is in excess of that needed to cause the gripping lever to engage the nut. Thus, when the machine is running at a high speed, the gripping action of the lever on the nut occurs during movement of the cam lever and as a result, if the parts become worn, undesirable impacts and irregularities in locking action of the presser foot mechanisms may occur between the cam lever and the nut as a consequence of vibration in the connecting parts.

The presser foot actuating mechanism of the application consists of a pair of ratchet arms, one of which is rigidly connected to the presser foot and the other yieldingly connected. The rigid ratchet arm is engaged by a locking pawl on a fixed pivot and the yielding ratchet arm by a cam actuated pawl to cause the presser foot to clamp the work intermittently during sewing. The difficulty with the use of pawls is in the uncertainty with which they engage the teeth of their ratchets and the consequent irregularity of clamping and locking action on the presser foot.

To avoid vibration in the presser foot actuating mechanism of a shoe sewing machine and to enable a presser foot to be moved with precision through its work clamping and releasing cycle, regardless of the speed of sewing, a feature of the present invention relates to the use of a wholly hydraulic presser foot actuating mechanism, the presser foot being actuated entirely by a presser responsive member without the use of springs or other motion retarding or impact producing devices. As illustrated in Fig. 1 of the drawings, the presser foot 10 has an arm 18 connected by a link 20 to a lever 22 fulcrumed on a stud 24 rigid in the machine frame. The lever 22 is directly connected to the pressure responsive member by a link 26. The only other

connections actuated during movement of the presser foot towards and from the work are those for controlling measurement of thread in accordance with the thickness of the work including an arm 28, a link 30 connected between the arm 28 and an arm 32 on a thread pull-off controlling rock shaft 34 acting in a manner similar to that described in the patents above referred to. These connections being light and relatively free from substantial strains at any time during stitch formation, have little or no effect on the movements of the presser foot and are not subject to wear to the extent encountered in the presser foot actuating connections where heavy actuating pressures occur.

The pressure responsive member consists of a piston 36 mounted to slide within an actuating cylinder 38 in the machine frame and having a piston rod 40 passing through the upper head of the cylinder and secured in a clamp block 42 to which the link 26 is pivotally connected. The cylinder head also supports a stop screw 44 arranged at its upper end to be engaged by a shoulder on the clamp block 42 to limit the movement of the presser foot away from the work support 8 when the machine is brought to rest. To apply fluid pressure to either end of the piston 36, the upper end of the cylinder 38 is connected with one end of a tube 46, the other end of which is connected with a drilled passage 47 (see Fig. 4) in a base 48 of a by-pass valve. The base 48 is suitably mounted on the side wall of a main rotary control valve housing 49 formed in the machine frame and constructed with suitable ports to connect the upper end of the cylinder 38 with a source of compressed liquid, preferably oil. The lower end of the cylinder 38 is connected through a tube 50 to another passage 51 in the control valve body which in turn is connected to an opening 52 in the housing for the main control valve.

During sewing operations, after the feeding movement of the work has taken place, the full pressure of the compressed oil is applied to the tube 50 and the lower end of the piston 36 to cause the presser foot to engage and clamp the work. Just before the work is again fed, the source of compressed oil is disconnected from the lower end of the piston and connected through a fluid metering device to the upper end of the piston to enable a limited amount of flow through the tube 46 and a uniform limited movement of the presser foot as it is raised from the work, the tube 50 simultaneously being connected to exhaust at atmospheric pressure.

The oil is compressed by a continuously driven pump 54 of well-known construction having a pressure relief valve 55 constructed to maintain the pressure uniform. The pump 54 is driven through a spur gear 56 on the main pump shaft meshing with a similar gear 58 on a counter-shaft carrying a driven pulley 60 for the low speed driving mechanism of the machine. The pulley 60 supports a driving belt 62 actuated by a suitable source of power in the main base of the machine.

Oil is supplied to the pump from a reservoir 64 through a suction tube 66 entering the lower part of the reservoir and connected with the intake side of the pump. The outlet side of the pump is connected to a pressure tube 68 having a compressed air storage chamber 69 and a discharge into a passage 70 (see Fig. 5) in the base 49 of the by-pass valve. The oil stored in the chamber 69 is available to actuate the piston

36 whenever required and through any distance even though the capacity of the pump to provide oil for the particular movement is momentarily exceeded. The by-pass valve has a cylindrical body 71 formed with a circumferential groove 72 through which the oil under pressure passes to a passage 74 in the base 48, into an opening 75 of the housing, and into a circumferential groove 76 in the cylindrical body indicated 5 at 78, of the main control valve, the housing 49 for which supports the base 48 (see Figs. 1 and 3). The circumferential pressure groove in the control valve body 78, as best shown in Fig. 7, is connected to an elongated pressure port 80 and 10 a relatively short port 82 arranged in axial alignment with the opening 52 in the main valve housing. The opening 52 registers with a corresponding opening 84 in the by-pass valve base 48 from whence the oil under pressure is conducted through the passage 51 and tube 50 to the lower end of the cylinder 38 to cause the presser foot 15 to engage and clamp the work.

To cause the presser foot to be raised a uniformly limited distance from the work during each sewing cycle, and to enable an accurate adjustment of the distance through which the presser foot is raised, the pressure groove 75 in the main valve body 78 is connected to a port 86 arranged to register with an opening 88 in the main valve housing leading into a passage 90 in the base 48 which enters one side of a cylinder 92 of the metering device. Within the cylinder 92 is slidably mounted an unrestrained piston 94 acting to prevent the flow of oil in one direction when the piston reaches the end of the cylinder and in the other direction when brought against the end of an adjusting screw 96 threaded through a packing nut 98 forming the outer head of the cylinder 92. From the forward end of the metering cylinder 92 there is a passage 100 (see Fig. 4) leading through the passage 47 and tube 46 to the upper end of the actuating cylinder 38. The arrangement is such that when the opening 88 is uncovered by the port 86, oil is caused to flow through passage 90 into the metering cylinder 92, moving the piston 94 against the end of the metering cylinder, thus forcing a limited supply of oil through the tube 46 to cause the presser foot to be raised a predetermined distance from the surface of the work. The distance through which the piston is raised may be regulated by changing the position of the adjusting screw 96 which determines the location of the piston 94 before it starts its movement towards the end 55 of the metering cylinder.

To enable oil to be exhausted from the upper end of the actuating cylinder 38 when the presser foot is actuated to clamp the work, the main control valve is provided with ports 102 and 104 arranged to be brought into registry with an opening 106 in the valve housing to which the passage 100 at the forward end of the metering cylinder 92 is connected. The ports 102 and 104 have passages extending radially into the valve body 78 and entering a central cavity 108 (Fig. 3) within the valve body. When the exhaust ports uncover the opening 106, both the upper end of the actuating cylinder and the forward end of the metering cylinder are vented at atmospheric pressure. The upper end of the cavity 108 is blocked by a flanged bearing 109 and the lower end of the cavity is opened to permit discharge downwardly into the reservoir 64. To exhaust the lower end of the main cylinder 38, the main valve body 78 has a port 110 arranged to be moved into registry with

the opening 52 with which the tube 50 is connected. The port 110 also discharges radially through the cavity 108 of the main valve body.

The main valve body 78 has an internal perforated hub, with a central opening in which is keyed the lower end of a vertical valve shaft 112 passing through the flanged bearing 109 and a bearing 113 on the machine frame. Above the bearing 113 is a helical gear 114 meshing with an idler gear 115 rotating on a horizontal stub shaft 116 in the machine frame. The idler gear in turn meshes with a gear 118 secured to the sewing shaft 16, the valve shaft being driven thereby at the same speed of rotation with the shaft 14.

It will be noted that as the control valve body 78 is rotated from stopped position of the machine, as indicated in Fig. 7, by the right-hand edge on the developed surface of the valve, that the openings 52 and 106 in the valve housing are uncovered first by the pressure port 82 and the exhaust port 104. Resulting pressure in the opening 52 causes oil to flow through the passages 84, 51, the tube 50 and the lower end of the actuating cylinder 38. Oil pressure on the lower end of the piston 36 causes the presser foot to clamp the work and the exhaust connection through port 104, opening 106, passages 100, 47, and tube 46 enables oil to flow as required from the upper end of the actuating cylinder. Continued rotation of the valve body again covers the openings 52 and 106 and causes ports 86 and 110 to uncover the openings 88 and 52, respectively, in the valve housing. Pressure through port 86 then forces oil through opening 88, passage 90 into the metering cylinder 92. As the oil moves into the cylinder 92, the piston 94 is carried away from the stop screw 96 towards the forward end of the cylinder displacing oil in front of the piston and causing it to flow through passages 100 and 47 and tube 46 to the upper end of the actuating cylinder 38. Uncovering the opening 52 by the exhaust port 110 enables the lower end of the actuating cylinder to vent through the tube 50 and passages 51 and 84 into the reservoir 64. The presser foot is accordingly raised through a distance corresponding to the amount of oil displaced by the metering piston.

After the feed of the work has been completed, openings 88 and 52 are momentarily closed and again uncovered by the exhaust port 108 and the pressure port 80, respectively. Uncovering the openings 88 and 52 by these ports causes a reverse flow of oil through the channels referred to and the presser foot is again actuated to clamp the work. At the same time, the port 102 uncovers the opening 106 in the control valve housing so that the upper end of the actuating cylinder is vented at atmospheric pressure.

The clamping force of the presser foot is maintained on the work as the valve body 78 continues to rotate beyond the left end of the developed surface in Fig. 7 until the ports 104 and 82 at the right end have been reached and passed. A brief period of cut-off is provided between the exhaust ports 102 and 104 and the pressure ports 80 and 82 which locks the presser foot in fixed position and prevents release of the work or change in pressure exerted on the work. During the portion of rotation which provides this cut-off period, the machine may be brought to rest, so that the by-pass valve may be brought into operation effectively to raise or lower the presser foot in stopping or starting the machine.

As in the machine of Patent No. 1,233,539, the

driving and stopping mechanisms are provided with a lever corresponding to that indicated at 120 which is actuated in one direction as the sewing shafts are brought to rest and in the other direction when the operation of the machine is started. In the illustrated machine, the lever 120 is connected through an adjustable link 122 to an arm 124 secured to a central boss on the bypass valve body projecting through a bearing in the base 48. When the machine is brought to rest, the by-pass valve is rocked in the direction of the "stop" arrow in Fig. 7 and when the machine begins its operations, the valve is rocked in the direction of the "start" arrow.

15 The by-pass valve body 71, in addition to the central groove 72, is provided with exhaust ports 126 and 128 having radial passages extending into a central cavity 130 of the body (see Fig. 5). The left end of the central cavity is closed by a plate 132 having an exhaust tube 134 leading into the reservoir 64. Pressure ports 136 and 138 are also provided in the valve body connecting with the central groove 72. When the machine is stopped, the pressure port 138 is moved into registry with a double opening 140 in the valve base 48, which opening is connected with the passage 47. At the same time, the port 138 uncovers the opening 149, the exhaust port 126 uncovers a double opening 142 connected with the passage 51 in the base 48. Thus, when the machine comes to rest with the openings in the control valve closed and the by-pass valve moves into the position of Fig. 7, pressure will be applied through port 138, opening 140, passage 47, tube 46, to the upper end of the cylinder 38, causing the presser foot to be disengaged and raised from the work. The lower end of the actuating cylinder 38 is vented through tube 50, passage 51, opening 142 and the exhaust port 126.

40 When the machine is started in operation, the ports 138 and 126 move away from the openings 140 and 142 and the ports 128 and 136 uncover these openings momentarily. The positions of the ports 138, 126 and 128, 136 being reversed so far as application of pressure and fluid exhaustion is concerned, a reverse movement will be imparted to the presser foot, causing it to clamp the work. In order to avoid interference with the normal operations of the presser foot to clamp and release the work during sewing, the by-pass valve is moved still further in starting the machine to a position with the ports 136, 128 out of registry with the openings 140 and 142, so that the by-pass valve no longer influences the movements of the presser foot.

45 From the foregoing description, it is apparent that all of the movements of the presser foot are produced and controlled by hydraulically actuated connections and that no direct mechanical locking devices or actuating mechanisms are relied upon to impart the requisite motions to linkages connected with the presser foot. Neither is it necessary to employ a mechanism having only a portion of its effective stroke utilized either for locking or actuating the presser foot, the remaining portion of the stroke being taken up by yielding or lost motion connections. Consequently, all of the joints between the connections may be made as rigid as practicable according to acceptable machine practices with a view to durability in prolonged use under adverse conditions. The rotary type of control and by-pass valve employed is particularly effective for transferring pressure 50 from one side of the piston to the other while

imparting the desired motions to the presser foot since the cut-off characteristics of valves of this type include a relatively gradual throttling action so as to soften the tendency towards impact in the hydraulic system. The throttling effect of the various ports in these valves as they reach a position out of register with the corresponding openings in the valve housings also reduces any tendency in the linkages connecting the actuating piston with the presser foot to vibrate, to such an extent that difficulty from this cause is insignificant even when operated at high speeds. In these respects, certain features of the present invention and the advantages obtained thereby are similar to those resulting from the use in a sewing machine of a hydraulic presser foot lock as disclosed in an application for U. S. Letters Patent of Baker, Serial No. 419,099, filed of even date herewith.

Having thus described the invention, what is claimed is:

1. A shoe sewing machine having, in combination, stitch forming devices, a presser foot, a work support and means for actuating the presser foot relatively to the work support to clamp and release the work comprising a liquid pressure responsive member and means for applying hydraulic pressure to and relieving the pressure from the responsive member during each sewing cycle of the stitch forming devices.

2. A shoe sewing machine having, in combination, stitch forming devices, a presser foot, a work support, and means for actuating the presser foot relatively to the work support to clamp and release the work comprising a hydraulic pressure responsive member, a pump for providing a continuous source of liquid under pressure, and a valve actuated during each sewing cycle to control passage of liquid from the pump to the pressure responsive member.

3. A shoe sewing machine having, in combination, stitch forming devices, a presser foot, a work support, and means for actuating the presser foot relatively to the work support to clamp and release the work comprising a hydraulic pressure responsive member, a pump for providing a continuous source of fluid under pressure, a valve actuated during each sewing cycle to control passage of fluid from the pump to the pressure responsive member, and a pressure storage chamber between the pump and the valve to supply fluid in greater volume than provided by the pump when the valve is opened.

4. A shoe sewing machine having, in combination, stitch forming devices, a presser foot, a work support, and means for actuating the presser foot relatively to the work support to clamp and release the work comprising a hydraulic pressure responsive member, a pump for providing a continuous source of fluid under pressure, and a valve for controlling passage of fluid from the pump to both sides of the pressure responsive member to cause the presser foot to be forced against the work and to be raised a substantial distance above the surface of the work during each sewing cycle.

5. A shoe sewing machine having, in combination, stitch forming devices, a sewing shaft for actuating the stitch forming devices, a presser foot, a work support, and means for actuating the presser foot relatively to the work support to clamp and release the work comprising a hydraulic pressure responsive member connected to the presser foot, a source of fluid under pressure, and a valve driven by the sewing shaft connecting

the source of fluid with the pressure responsive member.

6. A shoe sewing machine having, in combination, stitch forming devices, a sewing shaft for actuating the stitch forming devices, a presser foot, a work support, and means for actuating the presser foot relatively to the work support to clamp and release the work comprising a hydraulic pressure responsive member connected to the presser foot, a source of fluid under pressure, a valve driven by the sewing shaft connecting the source of fluid with the pressure responsive member, and a metering device connected between the fluid source and the pressure responsive member to limit the movement of the presser foot by said pressure responsive member.

7. A shoe sewing machine having, in combination, stitch forming devices, a sewing shaft for actuating the stitch forming devices, a presser foot, a work support, and means for actuating the presser foot relatively to the work support to clamp and release the work comprising a hydraulic pressure responsive member connected to the presser foot, a source of fluid under pressure, a valve driven by the sewing shaft connecting the source of fluid with the pressure responsive member, and a metering cylinder connected between the fluid source and the pressure responsive member, a piston in the metering cylinder, and an adjustable stop for restricting the piston in the cylinder to limit the movement of the presser foot by said pressure responsive member.

8. A shoe sewing machine having, in combination, stitch forming devices, a sewing shaft for actuating the stitch forming devices, a presser foot, a work support, and means for actuating the presser foot relatively to the work support to clamp and release the work comprising a hydraulic pressure responsive member connected to the presser foot, a valve driven by said sewing shaft connecting the source of fluid with the pressure responsive member, a metering cylinder connected between the fluid source and the pressure responsive member, a flow blocking piston in the metering cylinder, a stop for restricting the piston in the cylinder to limit the presser foot lifting movement imparted to said pressure responsive member, and a port in the valve for admitting fluid under pressure to the pressure responsive member to raise the presser foot from the work.

9. A shoe sewing machine having, in combination, stitch forming devices, a sewing shaft for actuating the stitch forming devices, a presser foot, a work support, and means for actuating the presser foot relatively to the work support to clamp and release the work comprising a hydraulic pressure responsive member connected to the presser foot, a valve driven by said sewing shaft connecting the source of fluid with the pressure responsive member, a metering cylinder connected between the fluid source and the pressure responsive member, a flow blocking piston in the metering cylinder, a stop for restricting the piston in the cylinder to limit the movement of the presser foot imparted by the pressure responsive member, and ports in the valve for exhausting the fluid from the pressure responsive member and the metering cylinder.

10. A shoe sewing machine having, in combination, stitch forming devices, a sewing shaft for actuating the stitch forming devices, a presser foot, a work support, and means for actuating the presser foot relatively to the work support to clamp and

release the work comprising a hydraulic pressure responsive member connected to the presser foot, a valve driven by said sewing shaft connecting the source of fluid with the pressure responsive member, a metering cylinder connected between the fluid source and the pressure responsive member, a flow blocking piston in the metering cylinder, a stop for restricting the piston in the cylinder to limit the movement of the presser foot imparted by the pressure responsive member, a first port in the valve for exhausting the fluid from one side of the pressure responsive member to enable the presser foot to clamp the work, and a second port in the valve for exhausting the pressure from one end of the metering cylinder while the presser foot is clamping the work.

11. A shoe sewing machine having, in combination, stitch forming devices, a sewing shaft for actuating the stitch forming devices, a presser foot, a work support, and means for actuating the presser foot relatively to the work support to clamp and release the work comprising a hydraulic pressure responsive member connected to the presser foot, a valve driven by said sewing shaft connecting the source of fluid with the pressure responsive member, a metering cylinder connected between the fluid source and the pressure responsive member, a flow blocking piston in the metering cylinder, a stop for restricting the piston in the cylinder to limit the movement of the presser foot imparted by the pressure responsive member, a first port in the valve for exhausting the fluid from one side of the pressure responsive member to enable the presser foot to clamp the work, a second port in the valve for exhausting the pressure from one end of the metering cylinder while the presser foot is clamping the work, and a third port in the valve for exhausting the other side of the pressure responsive member only, to cause the presser foot to be raised a distance from the surface of the work determined by the volume of fluid displaced in the metering cylinder.

12. A shoe sewing machine having, in combination, stitch forming devices, a sewing shaft for actuating the stitch forming devices, a presser foot and a work support for clamping and releasing the work during each sewing cycle, driving and stopping mechanisms for bringing the sewing shaft to rest with the stitch forming devices in predetermined relative positions, a hydraulic pressure responsive member connected to the presser foot, a source of fluid under pressure, a control valve driven by the sewing shaft for connecting the source of fluid with the pressure responsive member to cause the presser foot to clamp the work, and a by-pass valve actuated by the driving and stopping mechanisms for relieving the work clamping pressure on the responsive

member whenever the sewing shaft is brought to rest.

13. A shoe sewing machine having, in combination, stitch forming devices, a sewing shaft for actuating the stitch forming devices, a presser foot and a work support for clamping and releasing the work during each sewing cycle, driving and stopping mechanisms for bringing the sewing shaft to rest with the stitch forming devices in predetermined relative positions, a hydraulic pressure responsive member connected to the presser foot, a source of fluid under pressure, a control valve driven by the sewing shaft for connecting the source of fluid with the pressure responsive member to cause the presser foot to clamp and release the work, a by-pass valve actuated by the driving and stopping mechanisms having a port to relieve the work clamping pressure on the responsive member, and another port for admitting fluid under pressure to the responsive member to raise the presser foot from the work at the end of a seam.

14. A shoe sewing machine having, in combination, stitch forming devices, a sewing shaft for actuating the stitch forming devices, a presser foot and a work support for clamping and releasing the work during each sewing cycle, driving and stopping mechanisms for bringing the sewing shaft to rest with the stitch forming devices in predetermined relative positions, a hydraulic pressure responsive member connected to the presser foot, a source of fluid under pressure, a control valve driven by the sewing shaft for connecting the source of fluid with the pressure responsive member to cause the presser foot to clamp and release the work, a by-pass valve actuated by the driving and stopping mechanisms having a port to relieve the work clamping pressure on the responsive member, and another port for admitting fluid under pressure to the responsive member to raise the presser foot from the work at the end of a seam, and additional ports for causing the presser foot to again clamp the work as the machine is started in operation.

15. A shoe sewing machine having, in combination, stitch forming devices, a sewing shaft for actuating the stitch forming devices, a presser foot, a work support and mechanism for actuating the presser foot relatively to the work support comprising a hydraulic pressure member connected to the presser foot, a rotary valve connected to fluid confining spaces at the ends of the pressure member, a gear connected to the valve, and means driven continuously from the sewing shaft for rotating the gear to lock the presser foot in fixed position during a portion of each sewing cycle.
